UNITED STATES PATENT OFFICE.

HURLEY J. TURNER, OF EMDEN, MISSOURI.

JAW-CINCH.

1,370,618.

Specification of Letters Patent.

Patented Mar. 8, 1921.

Application filed April 12, 1920. Serial No. 373,333.

To all whom it may concern:

Be it known that I, HURLEY J. TURNER, a citizen of the United States, residing at Emden, in the county of Shelby and State of Missouri, have invented a new and useful Jaw-Cinch, of which the following is a specification.

This invention relates to restraining devices, and more particularly to devices of this character especially designed for securing an animal's jaws in a closed position, to permit the application of a stomach tube, and eliminate any possibility of the animal chewing the tube.

15 A further object of the invention is to provide a restraining device of this character which may be readily and easily applied to an animal's head, the device having means to permit of adjustment thereof, 20 thus adapting the device for use in connection with various sized animals.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 30 within the scope of what is claimed, without departing from the spirit of the invention.

Referring to the drawing:—

The figure illustrates a perspective view of the restraining device constructed in accordance with the present invention.

Referring to the drawing in detail, the device includes the jaw section 5 and nose section 6, the section 5 having its ends connected to the metal loops 7 and 8, and secured thereto by means of the securing elements 9, which may be in the form of rivets or the like, and which pass through the section 5.

15 The section 6, has its ends embracing the metallic loops 10 and 11 respectively, the ends being secured to the loops 10 and 11 by means of the securing elements 12. An adjusting strap indicated at 13 passes through the loops 8 and 11, and this strap is provided with a plurality of openings 14 adapted to accommodate the tongue of the buckle 15, by means of which the loops 8 and 11 may be adjusted toward and away from each other.

5 The loops 7 and 10 are connected by the draw strap 16, which has one of its ends se-

cured to the loop 10, the intermediate portion thereof passing around one of the bars of the loop 7, and through the loop 10 where the same passes through the buckle 17, 60 which is secured to the section 5 in any suitable manner.

Associated with the nose strap, is a head strap 18 which has its lower end connected to the ring 19, as at 20, while the ring 21 65 has connection with the buckle 22, through the strap 23, the apertured end of the head strap 18 passing through the buckle 22 to adjustably connect one end of the strap 18 to the ring 21.

70 These rings 19 and 21 have connection with the loops 7, 8, 10 and 11 respectively, through the medium of the angularly disposed strap elements 24, which have their ends secured to the loops and rings as indicated at 25.

75 Due to the construction of the head strap 18, it is obvious that the device may be adjusted for use in connection with animals' heads of various sizes. In the operation of 80 the device, if it is desired to administer medicine to an animal, and more particularly a horse, the restraining device is applied over the horse's head, the nose strap being adjusted so that when the draw strap 85 16 is tightened, the animal's teeth of the upper and lower jaws are held into close engagement with each other, permitting a stomach tube to be inserted between the incision teeth, and the molars.

90 Having thus described the invention, what I claim as new is:—

A restraining device including a nose section and a jaw section, a loop member secured to each end of each section, supporting straps having connection with the loop members, an adjusting strap for adjusting predetermined loop members with relation to each other, a draw strap having connection with one of the loop members and 100 adapted to pass through the adjacent loop member, and means carried by one end of the jaw section to secure the draw strap against displacement.

105 In testimony that I claim the foregoing as my own, I have hereto affixed my signature in the presence of two witnesses.

HURLEY J. TURNER.
